Letters Patent

The schedule referred to in these Letters Patent and making part of the same containing a description in the words of the said Israel White himself of his improvement in the instrument or tool called a Plough used by car-
penters & other artificers

The old or common Plough plane familiar in common use, consist of two irregular square shaped oblong blocks; one called the plough, having a narrow oblique mortise cut through it to admit the plane iron which performs the office of ploughing the furrows or grooves --

The other block is called the fence running parallel with the first and so connected by two wooden screws discriminated arms about one inch from the end of each block, that the upper surface of the fence when brought near the plough by means of screwing the arms, may pass under and in close contact with its lower surface. By a contrary movement they can be extended further apart & the adjustment depends upon a female screw working on one end of the arm upon the side of the plough together with a small screw set upon the opposite side working also upon the arm, to be tightened or slackened at pleasure, which regulation determines whatever distance the groove shall be cut. This is nevertheless difficult in the performance because an inconvenience presents itself whenever both arms are to be moved in such a manner that the position of the fence shall be brought parallel to the grooving plate and unless it is effected by measuring the distance with a rule at each end of the fence & tightening the screws not upon the arms, a great deal of tedious delay is usually experienced by the mechanic before the under side of the plough is firmly attached an iron plate divides into two parts between which & this the narrow oblique mortise already described, passes the plane iron secured by a wedge proper.

1151X

The main bars are the plain iron bars, being considered by law to be plough blocks, the furrow or groove is sunk into bars to and made every 10 feet, & its depth regulated by the following contrivance:—Upon the top of the plough block, a small trap plate is sunk immediately over a groove notches, passing thro' the plough to admit a iron block of trap called a bared to be moved up and down by means of a screw, covered by a cover underneath the trap plate, the lower end of the screw entering it is made fast to the upper part of the barrel, — The bottom of the barrel is firmly attached to a flat piece of plate iron of about 3 or 4 inches long, having an extensive notch cut out of the side next to the grooving plate, extending over the divided part of that plate where the plane iron, bared & as easily as desired, with the movement of the barrel.

This notched piece of iron is denominated a stop & when worked by the screw and barrel the whole is altogether known by the appellation of the stop, — The above is the old fashioned construction of a common plough plane whose arms when moved to measure any required distance from the fence, could never effect its parallelism with the grooving plate without recourse to the rule for adjustment the plough was always found laters and troubles & causing much delay. To obviate so manifest an imperfection and to keep the fence steadily in its required position when the proper distance of the groove is to be determined is the object of my improved invention upon the plough for which I claim the right to a patent it being wholly new & distinguished from any other invention heretofore known or discovered. It consists of three arms passing thro' the block nearly in a line with each other, the two outer ones being plain sliding cylinders & the middle one a screw & nut with several screws much after the same construction and size as the old plough arms are. By adjusting this screw arm with the nut attached to it the distance where the groove should be cut can be ascertained with great facility & precision, & the fence being kept steadily in its place is always parallel to the plate without

the danger of varying in the last degree from its position.

To regulate this stop, which determines the depth that grooves are to be cut, a small scale graduated to an inch, more or less is introduced, transversely on the side of the plough block, next to the fence. A small fixture is cut by the side of it, which an index is attached to the barrel, and is moved up or down with so that the stop may regulate the depth of the groove to any required dimension by adjusting the index when passing the graduations upon the scale.

This simple contrivance renders the plough of infinitely more value in its use to various agriculturists who depend upon its expeditious operations by saving much time otherwise lost in the adjustment to ascertain the distance & depth for grooving.
